Des. 238,894

Patented Feb. 17, 1976

238,894

DIRECTION INDICATOR FOR VEHICLES, SPECIFICALLY FOR CYCLES AND MOTORCYCLES

Henriette Joly, 22 Avenue Parmentier,
75 Paris 11°, France

Filed June 19, 1974, Ser. No. 480,687

Claims priority, application Switzerland April 18, 1974

Term of patent 14 years

Int. Cl. D10—06; D26—06
U.S. Cl. D48—32 E

FIG. 1

FIG. 2

FIG. 3

FIG. 1 is an isometric view taken from the front and one side of a direction indicator, specifically for cycles and motorcycles showing my new design.

FIG. 2 is a side view of the direction indicator shown in FIG. 1.

FIG. 3 is a front view of the direction indicator shown in FIG. 1.

I claim:

The ornamental design for a direction indicator for vehicles, specifically for cycles and motorcycles, as shown.
